CHOCOLATE CHICK

Ira Garb, Brooklyn, N. Y.

Application October 5, 1951, Serial No. 16,839

Term of patent 3½ years

(Cl. D82—2)

To all whom it may concern:

Be it known that I, Ira Garb, a citizen of the United States of America, residing at Brooklyn, in the county of Kings and State of New York, have invented a new, original, and ornamental Design for a Chocolate Chick, of which the following is a specification, reference being made to the accompanying drawing, forming a part thereof.

Fig. 1 is a front elevational view of a chocolate chick showing my new design;

Fig. 2 is a rear elevational view thereof; and
Fig. 3 is a side elevational view thereof.

I claim:

The ornamental design for a chocolate chick, substantially as shown.

IRIA GARB.
